UNITED STATES PATENT OFFICE

154,462

DESIGN FOR A HOLDER FOR GLOBULAR OBJECTS

Alberto A. Concepcion, Detroit, Mich.

Application May 6, 1947, Serial No. 138,851

Term of patent 14 years

(Cl. D35—3)

To all whom it may concern:

Be it known that I, Alberto A. Concepcion, a citizen of the United States of America, residing at Detroit, in the county of Wayne and State of Michigan, have invented a new, original, and ornamental Design for Holders for Globular Objects, of which the following is a specification, reference being had to the accompanying drawing, forming part thereof.

Fig. 1 is a perspective view of a holder for globular objects, showing my new design; and

Fig. 2 is a bottom plan view thereof.

The essential features of my design reside in the portions shown in solid lines.

I claim:

The ornamental design for a holder for globular objects, as shown and described.

ALBERTO A. CONCEPCION.
